UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

CALENDAR.

1,192,054.

Specification of Letters Patent. Patented July 25, 1916.

Application filed January 4, 1915. Serial No. 331.

To all whom it may concern:

Be it known that I, FRANZ A. FULLER, a citizen of the United States, residing in the city of Newark, in the county of Essex and 5 State of New Jersey, have invented certain new and useful Improvements in Calendars, of which the following is a full, clear, and exact description, such as will enable others skilled in the art to which it pertains to 10 make, construct, and use the same, reference being had to the accompanying drawings, and to letters of reference marked thereon, forming a part of this specification.

My invention relates to calendars, and its 15 object is to provide a simple and novel form of device of this character, which may be utilized for a number of useful purposes, such as to furnish a calendar, paper weight, paper clip, or other convenient and useful 20 device.

The present invention consists primarily in a novel calendar, hereinafter set forth, and, furthermore, this invention consists in the various novel arrangements and combinations of parts, all of which will be described in detail in the following specification, and then finally embodied in the 25 clauses of the claim.

The invention is clearly illustrated in the 30 accompanying drawings, in which—

Figure 1 represents a plan view of my improved calendar. Fig. 2 represents a side view of the same. Fig. 3 represents a plan view of my improved calendar, the calendar 35 cards and cover having been removed; and Fig. 4 represents a central section of my improved calendar, the cover being shown in an open position.

Similar letters of reference refer to like 40 parts throughout the specification and drawings.

In the drawings, *a* and *b* designate the plates of the clasp, preferably made of metal or any suitable material, which are provided 45 with up-turned ears *c*, which overlap and are mounted upon and secured by a pivot pin *d*, said plates being normally held closed under tension by the spring *e* coiled around said pivot pin. The front edge of the plate 50 *a* terminates preferably in a curved portion, which engages the front edge of the supporting plate *b*, said plate *b* being provided near its rear edge with an aperture *f*, by

means of which the device can be hung upon a nail or the like, if desired.

The plate *a*, near its side and front marginal edges is provided with a series of integral lugs *g*, which are preferably struck up from and extend upwardly from said plate, designed to provide means for properly positioning and holding a calendar card *h*, a series of calendar cards, a picture or the like. The lugs *g* furthermore provide means for positioning and guiding the cover or lid on the plate *a*.

A hinged lid or cover *i*, the lower half of which is preferably provided with an embossed portion to be utilized for advertising purposes, and the upper half of which is provided with a cut-out portion to expose 70 the calendar, picture or the like, is secured to the plate *a*, near the rear edge thereof, in the following manner. The lid or cover *i* is provided with a downwardly extending flange *j*, that portion of the flange at the 75 rear edge of the lid or cover being curled inwardly, to form a tubular bearing *k* for the reception of the wire rod or pintle *l*. The ends of the pintle *l* are bent downwardly, and pass through suitable apertures 80 *m* formed in the plate *a*, and are then clenched upon the under side of said plate.

A finger piece *n* pierced from the lid or cover *i*, is located near the front edge of the lid, thereby providing means for releasing 85 the lid from locking engagement with the lug *g*, said lug being provided with a pressed-out portion *o*, which has locking engagement with the flange of the lid or cover, adjacent to the finger piece *n*.

The parts of this device are preferably 90 made from sheet metal, and are of such shape as to lend themselves readily to manufacture by the use of suitable punches and dies.

Experience has demonstrated that the organization above described is a highly efficient one, and while the device described is the preferred embodiment of my present invention, I do not care to restrict myself 100 to the exact details of construction, combination and arrangement herein set forth, it being obvious that minor variations thereof, not involving the exercise of invention, may be made by any skilled mechanic, and such 105 departures from what is herein described and

claimed, not involving invention, I consider as within the scope and terms of my claim.

Having described the invention, what I claim as new and desire to have protected by Letters Patent, is

A device of the character described, comprising a plate, a pintle at one end of the plate, a cover provided with an embossed portion and with a cut-out portion, said 10 cover further provided with a downwardly-extending flange, the flange at one edge of the cover being curled inwardly to form a tubular bearing for pivotally arranging said cover on said pintle, holding or positioning 15 lugs formed on the plate to which the cover is secured, adapted to hold a card or the like

in position, a holding lug on the plate having holding engagement with said cover, a supporting plate pivotally connected to the first-named plate intermediate of their ends, 20 the front edge of the first-named plate engaging the front edge of the supporting plate and a spring coiled around the pivot to normally hold the plates together at one end of the same.
